UNITED STATES PATENT OFFICE

2,476,408

RHYTHM CALCULATOR

George Fisher, Chicago, Ill.; Geraldine T. Fisher, administratrix of said George Fisher, deceased, assignor, by direct and mesne assignments, to George F. Fisher, Jr.

Application August 3, 1944, Serial No. 547,905

18 Claims. (Cl. 235—78)

1

This invention relates to a calculator for determining the rhythm numbers and also the calendar dates corresponding thereto for various menstruation cycles.

An important object of the invention is to provide a calculator of this kind adapted to cover regular menstrual periods and normal variations thereof.

A further object of the invention is to provide a calculator for determining the two rhythm figures for any usual menstrual cycle.

Another object of the invention is to apply the calculator to determine the actual dates for any particular rhythm figures covering any of the usual menstrual cycles.

Still a further object of the invention is to provide for calendar determinations applying the rhythm figures for months of different lengths.

Another object of the invention is to provide a calculator of this kind which is generally of new and improved construction, characterized by simplicity of design as well as ease and facility in use and assembly.

Other objects of the invention and various advantages and characteristics of the present calculator will be apparent from a consideration of the following detailed description.

The invention consists in the several novel features of construction and operation which are hereinafter described, and more particularly defined by the claims at the conclusion hereof.

In the drawings which accompany and form a part of this specification or disclosure and in which like letters and numerals of reference denote corresponding parts throughout the several views:

Figure 1 is an assembly view of the calculator showing the parts in a position for determining the rhythm numbers for a cycle of 28 days; Figure 2 shows the calculator with the parts in position for determining the rhythm numbers for a menstrual cycle which varies from 26 to 30 days, the cycle beginning upon the tenth day of a 30 day month; Figure 3 is a sectional view of the calculator; Figure 4 is a plan or face view of the transparent outer part; Figure 5 is a plan or face view of the left or lowest side of one part; Figure 6 is a plan or face view of the right or highest side of a second part; Figure 7 is a plan or face view of the base or foundation part upon which the

2

other parts are movable and adjustable; Figure 8 illustrates a modification set for determining the rhythm numbers for a cycle which varies from 22 to 26 days; and Figures 9, 10 and 11 show fragmentary views of the days, left and right adjustable parts respectively, of Figure 8.

It has been determined that in a menstrual cycle, there is a sterile period beginning with the first day of menstruation, followed by a fertile period lasting for a number of days in which conception can occur, and then a period of sterility extending to the next menstruation. For a woman whose regular cycle is 28 days, these periods are 9, 8 and 11 days respectively.

15 In the same manner, a regular cycle of 20 days has periods of 1, 8, and 11 days respectively; and a cycle of 36 days has periods of 17, 8, and 11 days respectively.

Most normal menstrual cycles vary from 2 to 6 20 days, as from 20 to 25 days, 26 to 28, or 24 to 30 days, and it is somewhat difficult to calculate the rhythm numbers for these variations, and to carry over the periods from one month to another.

25 The present invention provides a simple, reliable, and easily operated calculator for making the determinations of the rhythm numbers and their application to months of different lengths.

It is assumed that a woman has determined by 30 observation over eight months or more, the shortest and longest periods in her menstrual cycle. The first two figures of her rhythm are important to her, the first of which indicates the sterile days at the beginning of her menstrual cycle, and the second indicates the number of days in her fertile period.

35 Referring now more particularly to the drawings, the calculator comprises a base member 10 preferably circular in form and of flat flexible material such as cardboard, metal, plastic, or any other suitable material.

In the outer marginal edges are graduations 11 containing designations from 20 to 40. Inside of the graduated portion 11 is a ring containing a 45 segmental portion 12 of the same circular extent as the graduations 11 marked with a distinguishing color such as blue. Within the ring 12 and spaced from the lower graduation 20 by a distance of three of the same graduations is a marker 13 preferably in the form of a block which occupies

the same circular proportionate space as one of the outer graduations 11. At the center of the base member is a perforation 14 for receiving a mounting pivot 15.

Rotatably mounted on the pivot 15 next to the base plate 10 is the right side adjustment part 15a having a portion 16 of a diameter to cover the outer graduated ring 11 of the base member 10 and a portion 17 of smaller diameter to extend within and to uncover the base marker 13. At one end connecting the portion 16 and 17 is a connecting shoulder 18, and at the other side connecting these portions is a shoulder 19 having an outer projection 20 which extends outwardly beyond the edge or periphery of the base member 10 to provide means for easily adjusting it at the right side of any of the graduations 11. At the base of the shoulder 19 is a ring segment 21 corresponding to the color ring segment 12 of the base member 10 and having a length corresponding to four of the graduations 11. These are divided into two graduations 22 which are preferably of the same color as the color segment 12 and two other segments 23 which are a lighter shade of the same color.

The left adjustment part 24 as shown in Figure 5 has a portion 25 with a diameter substantially the same as that of the portion 16 of the part 15a to cover the graduations 11 of the base member, and a portion 26 of reduced diameter substantially the same as the diameter of the portion 17 of the right adjusting part, which extends to the inner edge of the cooler ring segment 12. The portions 25 and 26 of larger and smaller radius are connected by a straight portion 27 at one side and by a shoulder 28 at the other side having a continued projection 29 which extends beyond the periphery of the base member 10 to form a finger hold portion for adjusting the left part. Extending from the base of the shoulder 28 is a ring segment 30 having a colored portion 31 of a width of two of the graduated spaces 11, and a portion 32 of lighter color having a width of one of the same graduations. Extending circularly in the portion 25 of larger radius is a curved slot 33 to embrace the inner and outer sides of the marker 13 of the base member which is therefore visible through the slot for a full length corresponding to fifteen of the graduated spaces.

And finally, there is an outer adjustment part 35 having an outer ring 36 divided into continuous graduations having 30 in one group and 31 in another group corresponding to months of 30 and 31 days respectively. Inside of the graduated ring 36 is another ring of corresponding graduations 37 which are at a distance from the center so that they register with the marker 13 of the base member which is visible through the slot 33 of the left member 24. It is preferable that this outer adjustment part 35 is made of transparent material so that the marker 13 and the colored sections in the ring 12 of the base member and 21 and 30 in the adjustable parts 15a and 24 respectively are easily visible through it, the numbers designating the days of the month being also plainly visible in the outer graduated ring 36.

To cover a month of 28 days, the transparent outer part 35 is preferably marked with numbers from 1 to 28 arranged relatively to the graduations 3 to 30 for a month of 30 days and at the inside of the graduated ring 37.

It would be sufficient to have the two outer rings of the movable part 35 of a transparent

nature, but by having the entire part made of transparent material, the outer surface of the left adjustment part 24 may have thereon printed directions for using the calculator or other subject matter which is visible through this outer part 35. On the projection 29 of the left part 24 is an arrow 40 preferably having a distinguishing color such as red to designate the left side of the number of days in the shortest menstruation period, and in the projection 20 of the other part 15a is an arrow 41 preferably having a different designating color such as black to designate the right side of the graduation in the longest menstruation period under consideration.

In operating this calculator to determine the rhythm numbers for any cycle, whether it be a single day or a number of days, the left adjustment part is moved so that its arrow is at the left of the number designating the cycle or the shortest variation thereof, and the right adjustment part is moved so that its edge as designated by the arrow is at the right side of the numbered graduation designating the day and the period or the number of days in the longest period. With the right and left parts in these positions turn the transparent outer disc until the number 1 appears directly over the marker 13 which is then visible through the slot 33 of the left adjustment part. The rhythm numbers are thus in advance of the color visible through the disc in the example as shown in Figure 1, the numbers appearing in color being from 10 to 17, so that the two rhythm numbers are 9 and 8. In a similar manner, the rhythm numbers may be determined for any usual period and for any ordinary variation menstrual cycles.

To use the calculator for calendar dates, it is necessary only to vary the position of the outer transparent disc so that instead of placing the numeral one upon or over the marker 13, the date of last menstruation be adjusted to that position, the calculator being set for the days of longest and shortest periods, the sterile and fertile dates may be actually determined and read from the calculator. That portion of the outer disc which represents the number of days in the month under consideration, should be used in connection with the marker 13, whether it be for a month of 28, 30 or 31 days. For a February having 29 days, an additional day may be added to the result. In the example shown in Figure 2, the rhythm numbers which may be calculated are 7 and 12, the sterile days will be from the tenth to the sixteenth of the month, and the fertile days being from the seventeenth to the twenty-eighth.

In the same manner, the rhythm numbers and the calendar dates may be easily and quickly determined for any regular or variable menstrual periods within the range of the calculator. For all practical purposes, this range of calculation is included between graduations 20 to 40 on the base member.

A simplified form of the calculator is shown in Figures 8 to 11, comprising a base 44, a left adjustable part 45, a right adjustable part 46, and an outer rotatable part 47, all connected together for relative rotation by a common pivot screw 48. The difference between this structure and that previously described is that the base member has a marker 49 which projects outwardly from the periphery where it is visible outside of the outer edges of the left and right parts 45 and 46. This marker projection is spaced four graduations from the lower end of

graduations 50 designating the high and low days in a cycle at the edge of the base member; the left rotatable member 45 has a portion 51 of outer diameter substantially the same as the outer diameter of the base member except between the left end marker 52 and the shoulder 53 where the intermediate portion 54 is of the diameter of the inner side of the graduated portion 50 of the base member; similarly the right part 46 has a portion 55 with an outer diameter substantially the same as the diameter of the base member with a reduced portion 56 between the right end marker 57 and a shoulder 58, this portion of reduced diameter being the same as the portion 54 of the left part and uncovering the numbered graduations 59 between the end markers for any variation of the graduations 50 from 20, the lowest number, to 40, the largest number contained therein; and the outer member 47 is circular in form, and has an outer diameter less than the diameter of the inner edge of the graduations 50 of the base member and corresponding thereto. The outer member is not necessarily transparent since no covered marker or open slot is necessary as in the other form of the invention, and the marker 49 visible at the outer edge of the base member 44 is substantially the width of one of the graduations of the base member and also of one of the graduations of the outer member 47, thus making it possible to set the outer member so that one of its number 1 graduations is placed opposite the marker 49 for determining the rhythm numbers, or to set any number in the edge of the outer member opposite the marker 49 for determining the calendar applications of the rhythm numbers, all as previously set forth.

In the projection 52 of the left member 45 are three graduations 60 in line with the graduations 50 of the base member, and in the projection 57 of the right adjustable member 46 are four graduations 61 in line with the graduations 50 of the base member. These graduations are added to those exposed between the left and right adjustable members in determining the so-called "fertile period."

With this construction, no slotted or transparent parts are necessary and although the method and theory of operation is the same, the parts are simpler to construct, to set and to operate.

The invention is not to be understood as restricted to the details set forth since these may be modified within the scope of the appended claims without departing from the spirit and scope of the invention.

Having thus described the invention, what I claim as new and desire to secure by Letters Patent is:

1. A rhythm calculator having a base with the edge graduated to represent days, a pair of parts having outer projections and movable from opposite sides of the base to visibly include any number of graduations between the projections designating days variations in length of the menstrual cycle, a spaced marker on the base, and a movable outer member having graduations corresponding to those of the base for determining the graduations of the marker from one side of the visible graduations of the base.

2. A rhythm calculator having a base graduated to represent days, a pair of parts having outer projections and movable at opposite sides upon the base to include any number of said graduations between the projections designat-

inating days variations in length of the menstrual cycle, a spaced marker on the base, each of the parts having portions adjacent the included graduations including a predetermined number of similar graduations, and a movable outer member having corresponding graduations for determining the number of graduations from the marker to the adjacent predetermined graduations and the number of graduations included between the parts and added to said predetermined graduations.

3. A rhythm calculator having a base with graduations to represent days in menstrual cycles, a pair of parts having terminal projecting portions and movable on the base to include any number of said graduations therebetween designating days variations in length of the menstrual cycle, a spaced marker on the base, each part having a designating portion of

several graduations adjacent its terminal portion, the base having a similar designating portion extending along its graduations and corresponding to the designating portions of said parts, and a movable outer member having graduations for determining the number of graduations from the marker to the adjacent designating portion and the total graduations included in and between said graduated portions.

4. A rhythm calculator having a base with graduations to represent days in menstrual cycles, a pair of parts having terminal portions projecting over the graduations and movable to include any number of said graduations therebetween designating days variations in length of the menstrual cycle, a spaced marker on the base, one of the parts having a slot through which the marker is visible, the other part having a portion of reduced sections which uncovers the slot of the first part, and a movable outer member having graduations corresponding to those of the base for determining the graduations from the marker to the adjacent terminal portion included between the movable parts.

5. A rhythm calendar calculator havin a base with graduations to represent days, a pair of parts having terminal portions projecting over and movable to include any number of said graduations therebetween designating days variations in length of the menstrual cycle, a marker on the base spaced a number of graduations from one end of the graduations thereon, and a movable outer member having graduations corresponding to those of the base, and designated as consecutive days of adjacent months so that the transparent outer member may be moved with respect to the marker to bring any date of a month in register with the marker for determining the extension of the rhythm calculations in the same and into adjacent months.

6. A rhythm calculator having a base with circular graduations to represent days, a pair of parts rotatably mounted upon the base and having opposite projections movable from opposite sides to visibly include any number of graduations

therebetween designating days variations in length of the menstrual cycle, a spaced marker on the base at a predetermined distance from one end of said graduation and on an inner circle with respect thereto, and a rotatable outer member

having graduations corresponding to those of the base for determining the number of graduations from the marker to one side of the visible graduations of the base in determining the rhythm numbers of a menstrual cycle, the said parts all being rotatable upon a common axis.

7. A rhythm calculator having a base with curved graduations to represent days, a pair of parts rotatable on the base having relatively opposed terminals projecting over and movable at opposite sides of the base to include any number of graduations therebetween designating days variations in length of the menstrual cycle, a spaced marker on the base, one of the parts having a curved slot through which the marker is visible, a movable transparent outer member having circular graduations on the same scale as those of the base to represent the days of consecutive months, and a common connecting pivot upon which the base and said parts are connected for relative rotary movement, the variation of the said parts causing a corresponding variation of the distance of the marker from the adjacent edge of the graduations included between said pair of parts.

8. A rhythm calendar calculator having a base with curved graduations to represent days, a pair of parts having opposed terminal portions projecting over the graduations and movable in opposite directions with respect to the base to include any number of graduations therebetween designating days variations in length of the menstrual cycle, a spaced marker on the base, and a rotatable outer member having graduations corresponding to those of the base and designated as the consecutive days of adjacent months, an additional graduation for 28 days terminating on the last day of one of the said months for determining rhythm calculations in the same month and in adjacent months having 28, 30 and 31 days.

9. A rhythm calculator, comprising a base with a circular graduation to represent days and a color ring at one side thereof, a pair of parts having opposite outer terminal portions projecting over the graduations and movable at opposite sides of the base to include any number of said graduations designating days variations in length of the menstrual cycle and a corresponding portion of the color ring therebetween, each of the parts having its terminal portion and extension of the color ring for a predetermined number of graduations, a marker on the base spaced a predetermined number of graduations from the lower numbered end of the base graduations and located inwardly of the color ring, the movable part adjacent the marker having a curved slot therein located within the color ring through which said marker is visible, and a movable transparent outer member having graduations representing consecutive dates of adjacent months and located upon a ring to overlie the color rings of the base and said pair of parts so that the said marker is positioned adjacent the graduations of the outer member and visible through the outer member and the said slot of the underlying part.

10. A rhythm calculator having a graduated base member, a pair of independent parts having opposite outer terminal portions to project over the base graduations and movable relatively to include any of the base graduations therebetween designating days variations in length of the menstrual cycle, an outer member having graduations corresponding to those of the base member and movable relatively over the parts, the base member and the movable parts being connected by a common pivot, the base having a marker spaced with relation to the graduations, and the terminal portions of the movable parts extending

beyond the edge of the base to provide finger-hold portions for adjustably moving the parts with respect to the base and said marker.

11. A rhythm calculator, having a circular base, a pair of parts pivoted on the base having relatively opposite terminal portions which extend beyond the edge of the base to provide adjusting finger-hold portions to include various portions of the edge of the base therebetween, the base having a marker and one of the parts having a slot through which the marker is visible when the part is moved, the other part having a reduced portion of reduced diameter to uncover the base marker, and a movable transparent outer member through which the marker is also visible, the base and outer member having edge graduations to represent days and the outer member and the parts being adjustable with respect to the graduation of the base to determine the rhythm numbers for any periods included in and between said graduated portion of the base.

12. A rhythm calculator having a graduated base member, a pair of independent parts having outer projections and movable relatively to include different numbers of the graduations of the base between the projections, a marker fixed with respect to the graduations of the base, one of the parts having a slot through which the marker is visible, the other part having a cut away portion to uncover the marker when the parts adjacent the marker are in overlapping relation, and a transparent member having graduations corresponding to those of the base member movable relatively over said parts and the marker visible through the slot of one of the parts with relation to the graduations of the transparent member.

13. A rhythm calculator having a graduated base, a pair of parts independently movable having relatively opposite projecting terminal portions adjustable to include any number of said graduations therebetween, a marker on the base member, one of the parts having a slot through which the marker is visible, the base member having a color line at one side of the graduations, the slotted part having a colored portion adjacent the terminal end extending for three graduations, the other movable part having a colored portion extending for four graduations adjacent the terminal thereof, and a transparent member with graduations movable relatively to the graduations of the base and to the said adjustable parts having graduations corresponding to those of the base member and the marker of the base member being visible through the slot of one of said parts and the colored portion of said parts and of the base member being also visible through the transparent member.

14. A rhythm calculator having a base member with curved graduations designating days, a pair of independent parts having opposite projecting terminal portions and rotatable relatively to include graduations of the base therebetween designating days variations in length of the menstrual cycle, a marker on the base member relative to the graduations thereof, a color ring at one side of the base graduations, one of the parts having a curved slot through which the marker is visible, beginning at a predetermined distance from the said terminal of this part, the terminal of the slotted part having a continuation of the color ring of the base member extending for three graduations, the more remote graduation having a lighter color than the other two graduations, the other part having a color portion extending

for four graduations in line with the color ring of the base and the two more remote graduations being of a lighter color than the adjacent two, and a rotatable transparent member with graduations corresponding to those of the base member designated with numbers indicating the days of adjacent months.

15. A calculator for determining the two rhythm numbers of a menstrual period, comprising a graduated base member, a pair of independent parts movable relatively to include any of the graduations of the base designating days variations in length of the menstrual cycle, a base having a marker in a predetermined location thereon, one of the parts having a recess through which the marker is visible, the parts having designating portions adjacent their indicating ends, each including a predetermined number of steps corresponding to the graduated base to be added to the steps included between the parts when designating any of the graduations, and a transparent member having graduations corresponding to those of the base member with calendar designations for indicating the number of days from the spaced marker to the adjacent end of the said designating portion on that part on which the recess appears.

16. A rhythm calculator having a relatively stationary base with graduations, a pair of movable parts to include any of the graduations designating days variations in length of the menstrual cycle, a marker on the base member, and an outer member having calendar graduations corresponding to the graduations of the base movable relatively over said parts and the marker and visibly related to the graduations of the base member.

17. A rhythm calculator having a base member with graduations representing days, a pair of superposed movable parts having relatively opposite projecting ends to include any number of said graduations between the ends designating

days variations in length of the menstrual cycle, a marker on the base member at a predetermined distance from one end of said graduations and visible at the outer edges of said parts, and a predetermined number of graduations at the said projecting end of each part adjacent to the graduations of the base member and visible between the parts, and an outer movable member having graduations related to the graduations of the base member and said parts.

18. A rhythm calculator having a circular base member with a limited arc of graduations at its edge representing days and a marker projecting from the edge a predetermined number of graduations from the lowest day graduation, a pair of circular rotatable members having edges extending over the said graduations and each terminating in a relatively opposite shouldered end portion which uncovers said graduations, the end portions disposed oppositely to include any number of graduations between said ends, the end position adjacent the marker having three graduations and the other end portion having four graduations in line with the base graduations, and a rotatable outer member having its edge graduated in consecutive numbers representing calendar month days and disposed at the inner edges of the base and parts graduations and corresponding in size thereto.
